(57) **CLAIM**

The ornamental design for a lamp as shown and described.

DESCRIPTION

1.1 is a bottom perspective view of the lamp;

1.2 is a top perspective view of the lamp;

1.3 is a front elevation view of the lamp;

1.4 is a right side view of the lamp;

1.5 is a top plan view of the lamp; and

1.6 is a bottom plan view of the lamp.

The dash-dash broken lines illustrate portions of the lamp which form no part of the claimed design.
